[57] CLAIM

The ornamental design of a flower pot holder, substantially as shown and described.

DESCRIPTION

FIG. 1 is a perspective view of a flower pot holder showing my new design, the portion of a chain link fence being shown in broken lines for illustrative purposes only;

FIG. 2 is a top plan view thereof;

FIG. 3 is a side elevational view taken from the right of FIG. 2;

FIG. 4 is a front elevational view thereof.

FIG. 1

FIG. 4
